HARRY A. FOOTHORAP, OF HARRISBURG, PENNSYLVANIA, ASSIGNOR TO ELLIOTT-FISHER COMPANY, OF HARRISBURG, PENNSYLVANIA, A CORPORATION OF DELAWARE.

WRITING-ADDING MACHINE.

1,331,338.

Specification of Letters Patent. Patented Feb. 17, 1920.

Application filed November 4, 1912. Serial No. 729,384.

To all whom it may concern:

Be it known that I, HARRY ARTHUR FOOTHORAP, a citizen of the United States of America, residing at Harrisburg, in the county of Dauphin and State of Pennsylvania, have invented certain new and useful Improvements in Writing-Adding Machines, of which the following is a specification.

10 This invention relates to writing adding machines of that type which embraces a typewriter and an adding mechanism.

The object of the invention is to produce a machine of the specified character equipped not only for column addition but also for cross addition known as cross-footing and also for grand totalizing, which is a mere continuation of the cross-footing operation to compute the grand total of several 20 parallel columns, the column adding devices being stationary and the cross-footing or grand totalizing device being movable to successive column positions for operation in conjunction with successive column adding 25 devices.

More specific objects of the invention will appear as the necessity for their accomplishment is developed during the progress of the succeeding description.

30 In the accompanying drawings:—

Figure 1 is a plan view of a portion of an Elliott-Fisher billing machine equipped in accordance with my invention.

Fig. 2 is a rear elevation thereof.

35 Fig. 3 is a sectional view of the machine with certain parts omitted.

Fig. 4 is a section on the line 4—4 of Fig. 2 looking in the direction indicated by the arrows.

40 Fig. 5 is a rear elevation of the cross-footer advancing mechanism in normal position.

Fig. 6 is a similar view of the same parts shown in the positions they occupy after 45 limited initial movement of the cross-footer advancing arm or crank, the lock being shown released to advance the cross-footer upon continued movement of the crank.

Fig. 7 is a similar view with the parts 50 in the position they assume at the end of the cross-footer advancement,

Fig. 8 is a view of the same mechanism with the parts in the positions they assume upon complete retraction of the cross-footer.

Fig. 9 is a perspective view of the cross-footer carriage and adjacent parts.

Fig. 10 is a front elevation of the cross-footer controlling device.

Fig. 11 is a detail sectional view of the device shown in Fig. 10.

Fig. 12 is a detail view of the extension bearing bracket for the actuator shaft, and

Fig. 13 is a detail perspective view of the frame extension plate.

Each part is indicated by its appropriate 65 reference character throughout the views. 1 indicates the frame and 2 the carriage of an Elliot-Fisher billing machine in which, as is well understood, the frame moves longitudinally of the platen, not shown, to 70 line space the writing while the carriage 2 moves transversely of the platen on the frame 1 to letter space the writing. The keys 3 operate the downwardly acting printing mechanism 4 and the numeral keys 75 operate through suitable intermediate connections 5, an actuator or master wheel 6 carried by an actuator shaft 7.

Supported by the frame 1 in rear thereof, is what is known as a register bar 8 upon 80 which are adjustably supported a plurality of column registers 9 so located that when the printing mechanism is in position to print in a given column on the work sheet, the master wheel or actuator 6 will be disposed in coöperate relation to the particular column register appropriated to such column. Each of the column registers includes a series of denominational members, carrying mechanism, a device for resetting the 90 carrying mechanism upon the retraction of the carriage 2 and a resetting lever by means of which the denominational members and the carrying devices as well may be reset to normal zero position. Therefore it is merely necessary to operate the typewriter in the usual manner to print a number in any desired column, the movement of the carriage incidental to the writing of such number serving to bring the 100 actuator 6 into coöoperative relation with the proper denominational members of the

registers and the rotation of the master wheel upon the depression of the keys to print, serving to rotate the denominational members to an extent corresponding to the 5 values of the keys depressed.

The carriage 2 is under the control of the keys and is drawn to the right by carriage propelling mechanism including spring drums 10 carried by the frame 1 and 10 connected to the carriage by tapes 11. The described mechanism is of ordinary and well known construction being exemplified in Patents Nos. 573,868 to R. J. Fisher and 829,971 to Laganke and Smith.

15 The cross-footer attachment with which my present invention is more particularly concerned is mounted at the right hand end of the machine and comprehends a cross-footing and grand totalizing register 12 similar in construction to the registers 9 and 20 designed to be operated by a second actuator or master wheel 18 mounted on an extension 14 of the shaft 7 beyond the right hand end 14 of the carriage. The actuators 6 and 13 25 being secured to the same shaft are operated in unison and are so spaced that they will simultaneously engage corresponding denominational members or number wheels of a column register 9 and the cross-footing 30 register 12. (See Fig. 1.) Thus upon the depression of a key the two registers will be simultaneously operated in corresponding degree to accumulate the same value.

The cross-footing register 12, unlike the 35 column registers 9, each of which appropriated to a particular column and none other, is designed to accumulate values printed in different column positions. For instance, in cross-footing the cross-footer 12 must 40 accumulate the several values printed in the several columns and accumulated in the several column registers so as to compute and register what is known as the cross-footing, to wit, the total value of numbers printed in 45 a horizontal row but in different column positions. Therefore, instead of remaining stationary with respect to transverse movement relative to the work sheet, as do the column registers 9, the cross-footing register 50 12 is mounted to move to different column positions so that after a number has been printed in a given column and accumulated in both a column register and the cross-footer, the latter will be moved to another column position so that when a succeeding number is printed in another column and accumulated in another column register, it will also be accumulated in the cross-footer.

55 60 To accomodate the cross-footer, the frame 1 of the machine is equipped with a frame extension 1^a at the upper end of which is a bracket 15 supplementing the two usual rear frame brackets 16 and 17, at the upper ends 65 of which the register bar 8 is ordinarily

mounted. Extending between the brackets 15 and 16 at their upper ends are two stationary guide bars 18 and 19, the latter being somewhat below and to the rear of the bar 18. These bars 18 and 19 constitute 70 guides for what may be termed a cross-footer carriage or a register carriage 20 including a head 20^a slidable on the guide 19 and adjustably supporting a vertically disposed stem 20^b, carrying at its upper end a 75 short register supporting bar 8^a slidable along the guide bar 18. Upon this short register bar 8^a, the cross-footing register 12 is adjustably secured just as the column registers 9 are secured to the bar 8. The carriage 20 also includes a stem 20^c having a bifurcated upper end 20^d to engage the head 20^a and fixed at its lower end to a guide bar 21 slidable in suitable bearings 22 carried by the brackets 15 and 16. The 80 cross-footer carriage 20 is thus properly guided in its movement to advance the cross-footer 12 to different column positions.

In the present embodiment of the invention, it is designed to lock the cross-footer 85 carriage in its column position and to provide manually operated means operative to first unlock the carriage and then shift the same to another column position where it is automatically relocked. Secured to the 90 carriage 20, as for instance, by attachment to the lower end of the stem 20^c and to a block 21' at one end of the guide bar 21, is a combined locking and ratchet bar 23 having notches 24 in its upper edge and formed at 100 its under side with long ratchet teeth 25. The notches 24 and teeth 25 are spaced to correspond with the adding fields or columns and co-operating with the notches 24 is a locking arm 26 mounted to swing from the 105 upper end of a bracket 27 extended rearwardly from the frame of the machine. The locking arm 26 is yieldingly urged toward its locking or engaging position by a spring 28 secured to the free end of the arm and 110 to the bracket 27, as clearly shown in Fig. 7, and the end of said arm normally engages one of the notches 24 of the locking bar 23 to hold the latter rigidly against movement in either direction. Extended 115 from front to rear of the machine and journaled in suitable bearings is a rock shaft 29 equipped at its front end with a crank 30 and having at its rear end a driving arm 31 upon which is pivotally sup- 120 ported a driving pawl 32 adapted to engage the ratchet teeth 25 of the bar 23 and yieldingly urged toward the bar by a spring 33 secured at one end to the arm 31 and at its opposite end to the tail piece 34 of the 125 dog 32. Obviously, the lock 26 must be withdrawn from the notch in the bar 23 before the latter and the cross-footer carriage can be shifted by the driving pawl 32. It is for this reason that in the normal 130

position of the parts the driving pawl 32 is disposed a slight distance in rear of the vertical face of the adjacent ratchet tooth, this relation of the parts permitting slight movement of the arm 31 before the pawl engages the tooth. (See Fig. 5). This lost movement is utilized to release the lock 26. At the upper end of the driving arm 31 is pivotally secured a releasing cam 35, the upper end of which is designed to engage a pin 36 projecting from the arm 26 and serving also as a point of attachment for the spring 28. The lower end of the releasing cam 35 is urged by a spring 37 into engagement with a stop 38 on the driving arm 31, the pintle of the pawl 32 serving as such stop in the present construction. It will thus be seen that the releasing cam 35 is fixed against swinging movement in one direction relative to the driving element 31 but is capable of such swinging movement in the opposite direction against the resistance of the spring 37.

In the normal position of the parts shown in Fig. 5 the locking arm 26 is engaged with the bar 23, the beak of the driving pawl 32 is a slight distance in rear of the next succeeding ratchet tooth and the upper end of the releasing cam 35 is directly under the pin 36 of the locking arm. If now the shaft 29 is rocked by the manipulation of the crank 30, the initial movement of said crank will cause the releasing cam 35 to raise the locking arm 26 out of engagement with the bar 23 and to simultaneously advance the driving pawl 32 into engagement with the adjacent ratchet tooth 25. The continued movement of the crank will now swing the driving arm 31 which, through the pawl 32, will advance the bar 23 and with it the cross-footer carriage 20 and cross-footer 12 to the next column position. Before this position is reached, however, the releasing cam 35 will have moved out from under the pin 36 and the locking arm 26 will rest upon the upper edge of the bar 23, ready to be drawn into engagement with the next succeeding notch 24 to accurately locate and lock the cross-footer in the next column position. As soon as the lock 26 snaps into its locking position, the crank 30 is released by the operator and is returned together with the parts secured thereto, to normal position by a retracting spring 39 secured, as for instance, to the hub of the driving arm 31 and to the bracket 27.

The limits of the normal stroke of the driving element 31, just described, are defined by stops 40 and 41 formed in a plate 42 and engaged by a spring pressed stop 43, carried by the handle 44 of the crank 30. The stop 43, carried by the crank, is normally disposed to engage the two fixed stops 40 and 41 but may be withdrawn from such

interfering relation by a finger piece 45 against the resistance of the spring 46, enclosed in the handle of the crank and normally retaining the stop in the position shown in Fig. 11.

It will be understood that each advance of the cross-footer to the next adjacent column is effected by the swinging of the crank 30 in the manner described, the operation of the mechanism being shown in Figs. 5 to 7, Fig. 5 illustrating the normal positions of the parts, Fig. 6 showing the positions assumed by the parts when the lock has been released and the driving pawl brought into engagement with a ratchet tooth, and Fig. 7 showing the positions assumed by the parts when the stroke has been completed and the locking bar, carriage and cross-footer relocked in the new column position. Fig. 5 also shows, of course, the positions reassumed by the parts upon the release of the crank and the retraction of the mechanism to normal position preparatory to a repetition of the cross-footer advancing operation.

When the cross-footer has reached the limit of its advance, it is of course necessary to retract it again to the first column position so that as succeeding numbers are written in the columns, it may again accumulate and register the cross-footing or the sum of two or more cross-footings as the case may be. To effect this retraction of the cross-footer, I provide a cross-footer retracting motor 47 which, in the present instance, is in the form of a spring drum carried by the frame of the machine, as shown in Fig. 2, and connected as by a metal tape 48 with the bar 23. When the cross-footer has advanced from its normal position, the motor 47 is of sufficient strength to retract it quickly to the position it originally occupied, to wit, the first column position but it is obviously necessary to move both the locking frame or dog 26 and the driving pawl 32 out of engagement with the bar 23 in order to prevent interference with this retractile movement. For this purpose provision is made for what may be termed an extraordinary movement of the crank 30, that is to say, a movement somewhat beyond the limit of its normal retraction. To accomplish this it is simply necessary to draw back the stop 43, carried by the crank, out of interfering relation with the upper fixed stop 40 and then swing the crank 30 to the position indicated in Fig. 8. This backward movement of the crank 30 from normal position accomplishes the complete release of the lock 26 and driving pawl 32 from the combined locking and ratchet bar 23. This release of the bar 23 from the lock 26 is effected by what may be termed an unlocking cam or a lock releasing cam 49 mounted at the upper end of the driving arm 31 in such po-

sition that it remains out of interfering relation with the lock 26, during the normal stroke of the driving arm to effect repeated forward movements of the rack bar 23 and 5 the cross-footing register. It will be seen, however, that when the driving arm is in its normal retracting position, shown in Fig. 5, the cam 49 will be in close relation to the pin 36 projecting from the locking arm 26. 10 Therefore, when the operating handle 30 is carried back beyond its normal retracting position, shown in Fig. 5, to the releasing position shown in Fig. 8, the cam 49 will ride under the pin 36 to lift the locking arm 15 26 out of engagement with the bar 23. The same releasing movement of the operating handle will cause the driving arm 36 to carry back the driving pawl 32 and will cause its tail piece 34 to contact with a re- 20 leasing stop 50, which is secured to the bracket 27. When the movement of the tail piece is thus arrested, slight continued movement of the driving arm 31 will cause the driving pawl 32 to swing on its axis and to 25 be entirely withdrawn from interfering relation with the teeth 25 of the bar 23. It will be understood, however, that the driving pawl will clear the teeth before the bar 23 is fully released from the lock 26 so that 30 the instant said bar is released it may be fully retracted by the motor 47 to the position shown in Fig. 2 to restore the cross-foooting register 12 to its normal or first column position. The handle 30 may 35 then be returned to normal position, shown in Fig. 5, but the locking of the register in its first position by the arm 26 is not necessary, as it is securely held at the limit of its movement by the motor. The first op- 40 erating movement of the handle may be from the position shown in Fig. 8 in which case the initial movement would merely be utilized to restore the operative relation between the bar 23, locking arm 26 and the 45 driving pawl 32 and continued movement of the handle will effect the advance of the register 12 in the manner heretofore described.

Having thus described by invention, what 50 I claim is:—

1. In a writing adding machine, the combination with traveling recording mechanism adapted to print in different columns, of a computing device bodily movable to 55 different column positions but stationary during the operation thereof, means for operating the computing device as the recording mechanism is operated to print in any column to which said computing device is 60 appropriated, and separate mechanisms for respectively advancing the recording mechanism and the computing device from one column position to another.

2. The combination with traveling record- 65 ing mechanism adapted to print in several

columns, of a computing device operative as the recording mechanism prints in different columns, said computing device being stationary during the operation thereof but bodily movable from one column to another, 70 and means for effecting the bodily retraction of the computing device.

3. The combination with traveling recording mechanism adapted to print in several columns, of a computing device operative as 75 the recording mechanism prints in any column to which the computing device is appropriated but stationary as to bodily movement during the traverse of a column by the recording mechanism, means for advancing 80 the recording mechanism, separate means for advancing the computing device to successive column positions, and a motor operative to cause the retraction of the computing device to its original column position. 85

4. The combination with a traveling carriage and recording mechanism movable therewith, of a separate register carriage, a computing register mounted on said register carriage, independent propelling mechanisms for the respective carriages, retracting mechanism for the register carriage, means for establishing a coöperative relation between the recording mechanism and the computing register, whereby the operation of the recording mechanism results in an operation of the register, and means for disconnecting the propelling mechanism of the register carriage from said carriage to permit the retraction of the latter. 95

5. In a writing adding machine, the combination with recording mechanism, of a computing register movable to different column positions, operating mechanism for said register, said operating mechanism being operatively related to the recording mechanism, means for locking the computing register in stationary position while the printing point of the recording mechanism is located in an adding field or column, means for releasing the computing register, and register propelling mechanism arranged to operate the releasing means and to propel the released register from one column position to another. 105

6. In a writing adding machine, the combination with a register laterally movable, means for moving the register and register locking means including a locking arm, and a notched bar coacting to securely hold the 110 register in position to be operated, and means for automatically releasing the arm from the bar when the register moving means is operated.

7. In a writing adding machine, the combination with a register laterally movable to different column positions, a register locking means including a locking arm, a notch bar coacting to securely hold the register in position to be operated, and register propell- 115 120 125 130

ling mechanism operative to effect the release of the register and to thereafter propel the same to the next column position.

8. In a writing adding machine, the combination with traveling recording mechanism, of a computing register mounted to travel independently of the recording mechanism and including a series of denominational members and carrying means, means whereby the operation of the recording mechanism will result in an operation of the computing register, means for locking the register in stationary position while the recording mechanism is traversing a column to which the computing register is appropriated, and means operative to release the register and to move the same to another column position.

9. In a writing adding machine, the combination with a traveling recording mechanism, of a computing register, means independent of the traveling recording mechanism for moving the computing register bodily to successive column positions, locking means operative to hold the computing register stationary in each column position while the recording mechanism travels across the column or adding field for which the register has been positioned, and means whereby the register moving means will effect the release of the register.

10. In a writing adding machine, the combination with a recording mechanism and a computing register shiftable to different column positions, of a ratchet bar movable with the register and a driving arm having a pawl to engage the ratchet bar and to advance said bar and register and means for retracting the register to normal position.

11. In a writing adding machine, the combination with recording mechanism and a computing register coöperatively related therewith, of a bar movable with the register and having ratchet teeth and notches, driving mechanism engaging the ratchet teeth of the bar to advance said bar and register to different column positions, and a locking member engaging the notches in the bar to lock the register when positioned and a retracting spring for the register.

12. In a writing adding machine, the combination with recording mechanism and a computing register coöperatively related therewith, of a bar movable with the register and having ratchet teeth and notches, driving mechanism engaging the ratchet teeth of the bar to advance said bar and register to different column positions, a locking member engaging the notches in the bar to lock the register when positioned and means whereby the driving mechanism will effect unlocking the bar prior to each advance thereof.

13. In a writing adding machine, the combination with recording mechanism and a

computing register coöperatively related thereto, of a ratchet bar connected to the register, driving mechanism engaging the ratchet bar to advance the register to different column positions, and a motor for retracting the register to its initial column position.

14. In a writing adding machine, the combination with recording mechanism and a computing register coöperatively related therewith, of a bar movable with the register and having notches and ratchet teeth, a locking device engaging the notches, driving mechanism engaging the ratchet teeth and operative to first release the notch bar from the locking device and to thereafter move said bar to advance the register from one column position to another, and a retracting motor connected to the bar.

15. In a writing adding machine, the combination with a typewriter including a frame, a carriage movable thereon, a printing mechanism movable with the carriage, of an extension from the frame of the typewriter, a register carriage mounted to travel on said frame extension, a computing register mounted on the register carriage, register actuating mechanism coöperatively related to the printing mechanism on the typewriter carriage, means propelling the typewriter carriage, separate means for propelling the register carriage to advance the register to different column positions, and means for retracting the register carriage to initial position.

16. In a writing adding machine, the combination with recording mechanism and a computing register coöperatively related therewith, of driving mechanism operative to advance the register to different column positions, a motor for returning the register to initial position, a lock holding the register in its column position, and means operated by the driving mechanism to cause the disconnection of the register from both the driving mechanism and the lock to permit the return of said register by the motor.

17. In a writing adding machine, the combination with traveling recording mechanism and a plurality of stationary column registers, of means for operating the column registers from the recording mechanism, a cross-footing register also under the control of the recording mechanism, and means for moving the cross-footing register to different column positions to be operated simultaneously with the respective column registers.

18. In a writing adding machine, the combination with traveling recording mechanism and a pair of spaced master wheels movable with the recording mechanism and under the control thereof, of a plurality of stationary column registers operated in succession by one of the master wheels and a

cross-footing register operated by the other master wheel and movable to successive column positions to be operated successively by its master wheel as the other master wheel 5 operates successive column registers.

19. In a writing adding machine, the combination with traveling recording mechanism and a pair of master wheels mounted to travel therewith and under the control of 10 the recording mechanism, a series of column registers stationarily mounted and each including a series of denominational members and carrying means, said column registers being arranged to be traversed and operated 15 by one of the master wheels, a cross-footing register including a series of denominational members and carrying means, said cross-footing register being arranged to be traversed and operated by the other master 20 wheel while said cross-footing register is stationary and said cross-footing register being movable to different column positions so as to be traversed and operated successively by its master wheel as the other master 25 wheel traverses and operates successive column registers.

20. In a writing adding machine, the combination with a traveling recording mechanism, of a computing register, means independent 30 of the traveling recording mechanism for moving the computing register bodily to successive column positions, locking means operative to hold the computing register stationary in each column position 35 while the recording mechanism travels across the column or adding field for which the register has been positioned, means whereby the register moving means will effect the release of the register, and means 40 for retracting the register when released.

21. The combination with a traveling recording mechanism movable to and across successive column positions or adding fields, of a computing register movable in one direction to successive column positions, means 45 for holding said register stationary in each column position while the recording mechanism is traversing the column, means whereby the recording mechanism will operate the register in each column position thereof, means for advancing the register repeatedly in the same direction to successive column positions, and means for retracting the register to its original position.

22. The combination with traveling recording mechanism adapted to print in several columns, of a computing device operative as the recording mechanism prints in any column to which the computing device 50 is appropriated but stationary as to bodily movement during the traverse of a column

by the recording mechanism, means for advancing the recording mechanism, separate means for advancing the computing device to successive column positions and means for 65 retracting the computing device to its original column position.

23. The combination with a traveling carriage and recording mechanism movable therewith, of a separate register carriage, a 70 computing register mounted on said register carriage, independent propelling mechanisms for the respective carriages, retracting mechanism for the register carriage and means for establishing a coöperative relation 75 between the recording mechanism and the computing register whereby the operation of the recording mechanism results in an operation of said register.

24. In a writing-adding machine, the combination with traveling recording mechanism and a pair of spaced actuators movable with the recording mechanism and under the control thereof, of a plurality of stationary column registers operated in succession by one of the master wheels, a cross-footing register operated by the other master wheel, propelling mechanism for the recording mechanism and separate propelling mechanism for advancing the cross-footing 90 register step by step in a single direction to a plurality of successive column positions beyond its original position, and means for retracting the cross-footing register to its original position. 95

25. In a writing-adding machine, the combination with a frame and carriage constituting relatively movable elements, a plurality of column registers and a cross-footing register carried by one of said elements, 100 propelling mechanism for moving the cross-footing register on its supporting element and in a single direction to a plurality of successive column positions beyond its original column position, recording mechanism 105 and a plurality of master actuators coöperatively related and carried by the other of said relatively movable elements, one of said master actuators co-acting with successive column registers and the other master actuator co-acting successively with the cross-footing register in different column positions, and means for retracting the cross-footing register to its original position after each complete cross-footing operation. 110 115

In testimony whereof I affix my signature in presence of two witnesses.

HARRY A. FOOTHORAP.
